LEE ALFRETON HERVEY, OF PERTH AMBOY, NEW JERSEY, ASSIGNOR OF ONE-THIRD
TO GEORGE W. TYRRELL AND ONE-THIRD TO FREDERICK CARR, BOTH OF PERTH
AMBOY, NEW JERSEY

STREET-CLEANER.

1,078,352.

Specification of Letters Patent. Patented Nov. 11, 1913.

Application filed October 31, 1910. Serial No. 590,022.

To all whom it may concern:

Be it known that I, LEE A. HERVEY, a citizen of the United States, residing at Perth Amboy, in the county of Middlesex 5 and State of New Jersey, have invented certain new and useful Improvements in Street-Cleaners, of which the following is a full, clear, and exact description.

This invention relates to street cleaning 10 machines, and particularly to machines of the vacuum or suction type, and has for its object the provision of suitable mechanism adapted to efficiently clean every part of the street that the machine passes over.

15 Reciprocating disintegrating apparatus is provided for laterally scraping the crevices between Belgian blocks, cobbles and the like. A rotary disintegrating means is provided for breaking up the larger masses of street 20 dirt, while auxiliary cleaning means for the street gutters, coacts with those above mentioned by disposing the material removed from the gutter directly in the path of the disintegrating appliances.

25 My invention further contemplates the provision of a novel suction apparatus which coöperates with the dirt loosening and disintegrating parts aforesaid; the particles of dirt, pieces of paper and the like 30 being conveyed to a suitable sorting chamber. I have further provided means for disrupting and disintegrating such paper and like material in said chamber, and for sorting the collected material and storing 35 the same in separate compartments. These compartments are provided with appliances for delivering the material therefrom into bags or like receptacles.

The street cleaning apparatus is mounted 40 upon a suitable automobile body, and is provided with power means, preferably separate and distinct from the vehicle motor; so that the action of the cleaning apparatus is not interfered with by changes in the 45 speed of the vehicle.

Other objects of my invention will be hereinafter set forth and more particularly pointed out in the appended claims.

In general, the mechanism affords means 50 for efficiently cleaning streets and for disposing of the material in the manner above described, the several elements of the mechanism coöperating to this end and the whole affording a street cleaning device which is

particularly well adapted to perform its 55 function.

In the drawings which form a part hereof, and in which like reference characters designate like parts throughout the several views: Figure 1 is a side elevation of the 60 apparatus; portions thereof being broken away to more clearly illustrate the construction employed. Fig. 2 is a rear elevation of the said apparatus, the bag supporting platforms being removed. Figs. 3 and 4 65 together form a plan of the lower portion of my street cleaning machine; the tank being removed; Fig. 3 showing the left hand side of the machine, and Fig. 4 the corresponding right hand portion, the center line 70 of the machine being indicated by the initial portion of the irregular line A—B which passes through the engine 4. Fig. 5 is a partial horizontal section taken through the 75 said tank, and Fig. 6 is a detail of the gutter brush. Fig. 7 is a detail view of a portion of the gutter brush elevating means. Fig. 8 is a fragmentary sectional view of the double reciprocating brush mechanism.

Referring to Fig. 1, a suitable vehicle 80 body 1, formed of channel irons and I-beams or the like, is carried upon wheels 2. The vehicle so formed is adapted to be steered by suitable steering mechanism 3, and is driven by a gasoline engine 4, or the like. 85 Uprights 5 support a tank or sorting receptacle 6, which is spaced a sufficient distance above the body of the vehicle to afford room for an exhaust fan 7 and other operating parts therebeneath. These parts 90 are driven independently of the vehicle by means of a gasoline motor 8, or the like, the shaft of which drives a counter-shaft 9 by means of a chain and sprocket drive 10, or the like. Shaft 9 is connected by means of 95 a belt 11 with the driving pulley of the fan 7 above referred to. A second counter-shaft 12 is driven from shaft 9 by means of a worm and gear 13 and chain and sprocket drive 14; the speed of shaft 12 being considerably less than that of shaft 9. Upon the forward extremity of shaft 9 is a beveled pinion 15 which meshes with a beveled gear 16 and drives the shaft 17 which extends laterally across the machine. A suitable 105 friction drive 18 is disposed at either extremity of shaft 17 so that power is transmitted therefrom via flexible shafts 19 to

the gutter brushes. Upon either side of the vehicle at the forward end thereof are disposed seats 20 for the driver; two seats being provided so as to enable the operator to accurately and properly control the movements of the machine, more particularly when traveling close to the curb. By reason of this particular arrangement of seats and the levers hereinafter referred to, the operator is able to watch the action of the particular gutter brush 21 which is in use at such time, controlling the same by means of its lever 22. Other levers are arranged upon the respective sides of each of these seats to enable the operator to control the several parts of the mechanism from either side thereof and to also control the automobile driving mechanism from either side. Power is transmitted from shaft 9 by means of a chain and sprocket drive 23 to a short shaft 24 which rotates a pair of crank disks 25 by means of the respective sprocket and chain connections 26. These crank disks are mounted upon spindles 27, which are journaled in suitable brackets 28 secured to the under side of the frame. Wrist pins 29 extend out laterally from the respective opposed faces of the disks 25 and are journaled in the extremities of the links 30. These links are respectively connected at their farther extremities by means of pins 31 with the supports 32, said supports each carrying a brush 33 and being reciprocably mounted between the guides 34. The rotation of shaft 24 hence effects a reciprocation of the brushes 33 and since the wrist pins 29 are spaced substantially 180° apart, the reciprocal movements of the respective brushes 33 will obviously be opposite at all times. These brushes serve to scrape out and loosen up the dirt in the crevices and are particularly useful where the machine is used to clean Belgian block pavements, and the like. Their scrubbing action, however, is also of value when the machine is used upon asphalt. The gutter brushes 21 and supporting parts therefor, are of peculiar construction and merit description at some length.

Referring to Figs. 3, 4 and 6, it will be seen that the brush proper 21 has one face thereof of substantially conical contour. The base of the cone, however, is not a sharp edge despite the fact that the cone is of but a scant height, since bristles are disposed in somewhat cylindrical formation as at 35 in order to properly conform the brush to and clean out the angle formed by the curb and the street surface. The particular form of brush shown is of importance in that it is especially well adapted to efficiently clean out this angular recess.

The backing 36 of the gutter brush is secured to a shaft or spindle 37, this spindle being disposed inside of a short length of pipe 38. Thrust-bearings 39 and 40 are pro-

vided at the respective ends of this pipe so that the brush is adapted to be freely driven; the upper extremity of spindle 37 being connected to the flexible shaft 19 above referred to. Secured to the outer side 70 of a plate 41 which is carried by the frame 1, are a pair of bracket bearings respectively designated 42 and 43 in which is reciprocably mounted a vertically disposed rod 44; said rod having a projection 45 75 upon one side thereof to adapt it to be operated from the lever 22 in the manner shown in Fig. 1. This projection is connected to a lever arm 46 by means of a link 47; the said lever arm being secured to a fixed shaft 48, upon which the lever 22 is mounted. The upper extremity of the rod 44 carries a roller 49 which is adapted to bear against the under side of a flange 50 which preferably forms an integral part of 80 a sleeve 51, which is mounted upon a stud 52. This stud is secured in any suitable manner to the plate 41 as shown in Fig. 6 at 52'. Laterally projecting from the stud 52 is a pin 53 which rides in a spiral slot 54 provided in the interior or bearing surface of the sleeve 51. A bracket 55 extends downwardly and preferably inwardly from the bottom of the sleeve 51 and has pivotally mounted upon the lower extremity thereof a 95 sleeve 56. The pipe 38 rides loosely in this sleeve 56 so that it may be reciprocated therein in the manner hereinafter described. One side of the flange 50 is enlarged or thickened to afford room for the reception of 100 two pins 57. An apertured block 58 is mounted upon these pins, the aperture of said block being adapted for the reception of the pipe 38 which is secured thereto in any suitable manner, as for example, by a 105 set screw 57'. The holes through which the pins 57 extend are disposed upon either side of the pipe receiving aperture, and the said block is preferably mounted substantially midway of the length of said pins; 110 helical springs 59 and 60 being disposed upon the respective sides of said block, these springs being maintained under compression by means of washers 61 which are held 115 upon the extremities of the pins in any suitable manner. The construction just described affords considerable lateral play for the gutter brushes. If for example, the brush is in contact with the curb as shown in Fig. 6, and the machine is driven somewhat too close to said curb, the pipe 38 and driving parts will rotate about the pivotal point 62 of the sleeve 56, thereby compressing springs 60.

In operation should it be desired to raise 125 the gutter brush out of contact with the street to clear an obstruction or for other reasons, it is merely necessary to raise the lever 22, which by reason of its linked connection with the rod 44 will urge the sleeve 130

51 upwardly, thereby raising said brush. By reason of the spiral or cam-acting slot 54 and pin 53, sleeve 51 will be rotated at the same time that it is being raised, and hence 5 the gutter brush will be not only raised, but will be swung outwardly. A disintegrating brush 63 is pivotally suspended from the shaft 12 above referred to; said brush being so mounted that it is adapted to be driven 10 in the direction indicated by the arrow in Fig. 1, in any position in which it may chance to be held. Shaft 12 is journaled in brackets 64 which are secured to the rear end of the supporting frame, and the respective 15 extremities of said shaft carry beveled gears 65 which are in mesh at all times with the respective beveled pinions 66. Between each gear 65 and the corresponding bracket 64 is a collar 67 loosely mounted upon said shaft, 20 such collar forming part of a depending bracket 68 which is preferably secured to a cylindrical body or sleeve 69, as shown in Fig. 2, said bracket being omitted in Figs. 3 and 4 for clearness. The short shaft 70 25 upon which the pinion 66 is secured extends down through this sleeve and carries a second pinion 71 upon the lower extremity thereof, the latter pinion in turn meshing with the beveled gear 72, which is mounted 30 upon the extremity of a shaft 73 which carries the disintegrating brush 63 above referred to. Back of each of the bevel gears 72 is a collar 74 which corresponds to the collars 67 mounted upon the shaft 12; this collar 35 also forming part of a bracket 75' which is of substantially the same construction as bracket 68, and is preferably united to the lower extremity of the sleeve 69. Shaft 73 therefore is suspended from shaft 12 and is 40 also driven therefrom. The disintegrating brush 63 will, as it is drawn along, encounter irregularities in the street surface, but will tend to remain in contact with such surface while being positively driven at all times; 45 the shaft 73 being preferably rearwardly disposed with respect to shaft 12 so that the weight of the brush and other parts hereinafter referred to tend to hold said brush in close contact with the street.

50 A plurality of suction nozzles or mouths 75 of a novel type are disposed to the rear of the disintegrating brush 63, and it may be here noted that this disposition of such nozzles is particularly advantageous since, 55 should a brush be placed to the rear of the mouths of the suction apparatus, dirt disturbed by such brush would not in all cases be collected by the machine. Hence, the rearmost operative elements carried by the 60 machine are the said suction mouths. Each of the nozzles 75 tapers laterally upwardly and inwardly toward the upper extremity thereof, said extremity being preferably annular to permit of its ready engagement 65 with a section of flexible tubing or hose 76.

I prefer to provide a plurality of suction mouths which are separate and distinct from each other so that when an obstruction, such as for example, a brick, or the like, is encountered by one nozzle, such part 70 is free to swing upwardly to clear such obstruction without disturbing the remaining nozzles or raising them from the street surface. The nozzles 75 have their forward walls, adjacent the respective suction openings, preferably flared slightly as at 77 and the rear edge of each of these openings is provided with a somewhat flexible flap 78, which may be of thick leather or the like; such flap dragging along over the street surface and serving to substantially prevent the entrance of air from the rear; and forcing practically all of the air to enter the same from the front, whereby such air will carry the entrained dust and particles 75 churned up by the disintegrating brush directly into the suction mouths. The flexible pipe sections 76 deliver into a manifold 78, the latter in turn opening into the inlet aperture of the exhaust fan. The air is exhausted from the lower peripheral portion of this fan and is conveyed via the conduit 79 into the first compartment of the tank 6. This tank is preferably divided into seven compartments respectively designated 80, 81, 82, 83, 84, 85 and 86. As the dirt laden air emerges from the flared mouth of the conduit 79 it encounters a disintegrating plate 87 which is disposed in compartment 80. This plate is preferably of cheap construction so that the same may be readily replaced as it wears out in use. I find that a suitable form of this plate is made by merely punching up jagged or angular tongues from the surface thereof, such 85 tongues or prongs being directed toward the mouth of the conduit 79. The air blast delivered against these prongs causes pieces of paper, leaves and the like to be driven thereagainst with considerable force and to 90 be torn up and disintegrated thereupon. This plate further serves as a means of protecting the first of the screens hereinafter referred to, which is disposed immediately behind the said plate; such protection being 95 desirable since small stones and the like will be hurled with considerable violence out of the conduit 79.

The several compartments are separated 100 from each other by means of a plurality of screens respectively designated 88, 89, 90, 91, 92, and 93. These screens are substantially vertical, but preferably have a slight inclination as indicated in Figs. 2 and 5; the inclination being such that material hurled 105 thereagainst which will not pass through the screens will work its way downwardly and slightly forwardly toward the bottoms of the respective compartments; thus preventing the cumbering up of said screens. The 110

screen 88 is preferably of relatively coarse mesh being made of heavy wire, and one inch openings being provided. Screen 89 is made of somewhat smaller wire and has 5 three-quarter inch openings. Correspondingly, screen 90 may have half-inch openings; 91 one-quarter inch; 92, one-eighth inch; and 93 one-sixteenth inch openings. A very efficient means for sorting the dirt 10 is afforded by this arrangement; particles of successively decreasing size being separately collected. The current of air passes successively through the several compartments escaping from screen 93 into a centrifugal separator 94. Here practically all 15 minute particles of dust which have passed screen 93 are separated from the air by centrifugal action and fall into the hopper which forms the bottom of the separator. The current of air then escapes upwardly 20 through the conical covers which are disposed at the top of the separator. The mechanism is hence adapted to sort dirt collected from the street into as many grades 25 as desired; the fine dust from the centrifugal separator being withdrawn from the spout 95, while the coarser grades are drawn off from spouts 96.

Suitable gates 97 are provided in connection 30 with each of the spouts, and the extremities of these spouts are preferably flanged or rimmed so that bags 98 may be secured thereto. Platforms 99 are provided at either extremity of the machine for supporting these bags and, if desired, these 35 platforms may be hinged as at 100 to permit of their being raised out of the way when not in use. I prefer to provide a hood 101 for the upper half of the disintegrating brush 63, which hood is supported in any 40 suitable manner from the sleeves 69. The cross frame 102 is pivotally connected to sleeves 69 and carries laterally extending arms 102'. The laterally extending arms 45 102' of cross frame 102 are pivotally mounted upon levers 103, one of which levers 103 is disposed adjacent either side of the machine. The levers 103 are fixedly mounted upon a rock shaft 104 which is journaled in 50 bracket 104' depending from the under side of the vehicle body. Shaft 104 is rocked by means of either of two links 105, which are in engagement at their forward extremities with the respective lever arms 106 and at 55 their rear ends with the respective lever arms 106', the latter being carried upon the extremities of shaft 104. The extremities of the cross frame 102 are pivotally connected at 107' with the sleeves 69 and each of the 60 links 105 is operatively connected to an operating lever 107, adjacent one of the seats 20 by means of a lever arm 106, which is carried by the shaft 48 above referred to. Hence the disintegrating brush may be 65 raised backwardly and upwardly when de-

sired by the operator. The cross-frame 102 is provided with a series of lugs 108 to which are pivotally connected the links 109. These links are provided with slots 110 for the reception of pins 111 which are secured 70 to the respective nozzles 75. By reason of the slotted connection aforesaid each of the nozzles can rise independently upon encountering an obstruction, while all of said nozzles will be raised whenever the rotary disintegrating brush 63 is elevated; as upon encountering the limb of a tree, for example. This is an important feature since when small obstructions are encountered practically only one of the nozzles will be disturbed, especially when such obstructions are sufficiently low or small in area to permit of the disintegrating brush riding thereover without being materially raised thereby. For similar reasons, the reciprocable 85 brushes 33 are also made raisable by means of the respective pairs of links 112 which are pivotally connected to the channels 32, and to connecting links 113, one of which is disposed adjacent either side of the machine. The connections between links 112 and 113 are preferably slotted as indicated at 112' to allow for the reciprocation of brushes 33 in the manner aforesaid, and each link 113 is connected to a bell-crank 95 113' which is operable by means of a lever 114. The respective levers 114 are mounted upon a hollow shaft 115 which is disposed around the stationary shaft 48 and extends across the machine as indicated in Fig. 4. 100 Mounted adjacent the respective ends of the fixed shaft 48 are levers 116 which are connected by springs 117 with a pivoted arm 118 which carries a friction wheel 119 and one extremity of the flexible shaft 19, which 105 is driven by said wheel. Each of the wheels 119 is adapted to frictionally engage a wheel 120, one of which is mounted at either end of the shaft 17 above mentioned. Obviously when either spring 117 is placed under tension the corresponding gutter brush will be 110 driven.

Each of the operating levers above described is provided with a suitable detent and operating handle 121 therefor; the detents being of any ordinary construction and adapted for engagement with the respective quadrants 122 so that said levers may be held in any position desired.

As aforesaid, each operative element of 120 the mechanism is hence actuatable from two positions, one upon either side of the machine and this obviously affords the operator every facility for manipulating a necessarily rather bulky apparatus. In so far 125 as I am aware this system of dual control has never before been applied to mechanisms of this or like character.

In conclusion particular attention is called to the disintegrating action of the 130

reciprocable and rotary brushes. The reciprocable and rotary brushes, or some of them, should preferably be formed of fairly stiff wire or stiff ratan of suitable strength to 5 disintegrate masses of clay or the like.

By reason of the lateral reciprocation of the brushes first encountered, which it will be observed sweep with a regular stroke back and forth across the street surface, 10 bearing against such surface with substantially uniform pressure at all times, there is no pronounced tendency to throw the dirt away from the machine, but merely to loosen and break up frangible particles or 15 masses thereof.

The rotary brush sweeps substantially at right angles to the reciprocable brushes and hence tends to disrupt particles which may have resisted the action of the latter. This 20 brush sweeps directly toward the suction mouths. The latter are not directed wholly toward the rotary brush but principally toward the street surface so that as the particles pass therebeneath they are drawn up 25 into the nozzles and practically no dirt or dust can escape.

What I claim, is:

1. A street cleaning mechanism comprising a dirt loosening brush, a frame, pivoted 30 members for supporting said brush whereby the latter may be dragged along by said frame, driving mechanism for said brush, a flexibly mounted suction mouth having the opening thereof disposed adjacent and to 35 the rear of said brush, means for simultaneously elevating both the brush and the suction mouth above the surface of the street when desired, both said suction mouth and brush being adapted to swing rearwardly 40 and upwardly upon encountering an obstruction in the street, said suction mouth being further movable rearwardly and upwardly independently of the brush.

2. A street cleaning machine comprising 45 a frame, a rotatable dirt loosening brush, means pivotally mounted on the frame for

pivots connecting said brush thereto, means for rotating said brush, a plurality of flexibly mounted suction mouths supported independently of each other and having 50 their inlets to the rear of and adjacent to said brush and mechanism for raising said brush and suction mouths, said suction mouths being further raisable independently of each other and of said brush when 55 one of said mouths encounters an obstruction in the street during the progress of the machine therethrough.

3. A street cleaning mechanism comprising a dirt loosening brush, a frame, pivoted 60 members for supporting said brush whereby the latter may be dragged along by said frame, driving mechanism for said brush, a flexibly mounted suction mouth having the opening thereof disposed adjacent said 65 brush, means for simultaneously elevating both the brush and the suction mouth above the surface of the street when desired, both said suction mouth and brush being adapted to swing rearwardly and upwardly upon 70 encountering an obstruction in the street, said suction mouth being further movable rearwardly and upwardly independently of the brush.

4. A street cleaning machine comprising 75 a frame, a dirt loosening brush connected to said frame, means for rotating said brush, a plurality of flexibly mounted suction mouths supported independently of each other, and mechanism for raising said 80 brush and suction mouths, said suction mouths being further raisable independently of each other and of said brush when one of said mouths encounters an obstruction in the street during the progress of 85 the machine therethrough.

In witness whereof, I subscribe my signature, in the presence of two witnesses.

LEE ALFRETON HERVEY.
